L. SPIRO.
INVISIBLE LOCK FOR METAL BEDS.
APPLICATION FILED APR. 20, 1921.

UNITED STATES PATENT OFFICE.

LEON SPIRO, OF EVERETT, WASHINGTON.

INVISIBLE LOCK FOR METAL BEDS.

1,403,206.

Specification of Letters Patent. Patented Jan. 10, 1922.

Application filed April 20, 1921. Serial No. 462,860.

To all whom it may concern:

Be it known that I, LEON SPIRO, a citizen of the United States, residing at Everett, in the county of Snohomish and State of Washington, have invented certain new and useful Improvements in Invisible Locks for Metal Beds, of which the following is a specification, reference being had therein to the accompanying drawings.

10 This invention relates to an invisible lock for metal beds, and the object of the invention is the construction of the legs of a bed or couch, or the like, which embody means for efficiently locking the side irons or rails of a bed to the leg or leg structure.

With this and other objects in view, my invention comprises certain novel combinations, constructions and arrangements of parts as will be hereinafter described, illustrated in the accompanying drawings, and more particularly pointed out in the appended claims.

In the drawings:

Figure 1 is a view partly in elevation and partly in section of a leg structure constructed in accordance with the present invention, while

Figure 2 is a section taken on line 2—2, Fig. 1.

30 Figure 3 is a view, in elevation, of the auxiliary section of the leg structure.

Figure 4 is a fragmentary, perspective view of one of the angle irons or rails of a metal bed.

35 Figure 5 is a fragmentary view, in elevation, of an embodiment of the primary section of the leg structure, while

Figure 6 is a fragmentary, perspective view of another embodiment of the angle iron or rail of a metal bed.

Referring to the drawings by numerals, 1 designates the primary hollow section of the leg structure, it being understood that in the construction of a bed or couch, or the like, 45 there are four leg structures used but it is only necessary to illustrate and describe one leg structure, as all used in the construction of a bed are duplicates. Rotatably mounted within the primary section 1 is an auxiliary section 2; the auxiliary section 2, like the primary section 1, is hollow and preferably cylindrical in shape (Fig. 2). On the lower end of the auxiliary section 2 is an ornamental flange 3, against which the lower end 50 of the primary section 1 rests. By gripping

flange 3 and turning same, the auxiliary section will be turned or rotated within the primary section 1. A suitable caster 4 is attached to the auxiliary section 2 and supports the primary section 1.

60

The primary section 1 is provided with a vertically-extending slot 5, which is sufficiently wide to allow the catch 6 on the angle iron or rail 7 to enter the primary section, and extend through the tapering opening 8 65 formed in the side of the auxiliary section 2; this opening 8 registers with the vertical slot 5. The bottom edge 9 of the opening 8 is on the same horizontal plane with the lower end of the slot 5 so that the lower edge of the catch 6 rests on the lower edges or bottoms of the slot 5 and the opening 8, Fig. 1. The top or upper end 10 of the opening 8 (Fig. 3) is inclined from one side to the other side of the opening, so that the catch 6 can enter 70 the highest end of the opening 8 and, then, by turning the auxiliary section 2, the upper edge 10 of the opening will ride through the slot 10^a of the angle rail 7 until the lowest portion of the upper edge 10 of opening 8 is 75 resting snugly in the slot 10^a, as seen in Fig. 1, thereby securing and fastening the angle iron 7 against displacement off the primary and auxiliary sections 1 and 2, respectively.

80 In the embodiment shown in Figs. 5 and 6, 85 the same principal is involved except that the primary section 1^a is provided with a pair of slots 5^a, and the rail 7^a is provided with a pair of catches 6^a, adapted to enter slots 5^a and be secured therein by an auxiliary section 2, as hereinbefore described.

90 While I have described the preferred embodiments of my invention, and have illustrated the same in the accompanying drawings, certain minor changes or alterations 95 may appear to one skilled in the art to which this invention relates, during the extensive manufacture of the same, and, I, therefore, reserve the right to make such alterations or changes as shall fairly fall within the scope 100 of the appended claims.

What I claim is:

1. In a device of the class described, the combination of a primary hollow section, an auxiliary hollow section within the primary 105 hollow section and supporting the same, said primary and auxiliary sections provided with registering slots or openings, and a rail provided with a catch adapted to enter said registering slots or openings and be 110

locked upon said sections when the auxiliary section is slightly rotated within and independently of the primary section.

2. In a device of the class described, the combination of an auxiliary section provided at its lower end with a flange, said auxiliary section having a large opening formed in its side, said opening having a horizontal straight lower edge and an inclined upper edge producing a wide end and a narrow end of said opening, a primary section over said auxiliary section and resting at its lower end upon said flange, said primary section provided with a vertically-extending slot registering with the opening of

said auxiliary section, a rail provided with a catch, and a slot on the rail between the rail and the catch, said catch adapted to extend through the slot of the primary section and through the opening of the auxiliary section and rest upon the bottom edges of the slot and the opening, said auxiliary section adapted to be rotated for placing the narrow end of the opening in the slot between the rail and the catch for locking the rail upon the sections, substantially as shown and described. 20 25

In testimony whereof I hereunto affix my signature.

LEON SPIRO.
